UNITED STATES PATENT OFFICE.

JESSE SPURGEON, OF OTTUMWA, IOWA.

CALCULATING-MACHINE.

1,160,337.

Specification of Letters Patent. Patented Nov. 16, 1915.

Application filed August 12, 1914. Serial No. 856,334.

To all whom it may concern:

Be it known that I, JESSE SPURGEON, a citizen of the United States, residing at Ottumwa, in the county of Wapello and State 5 of Iowa, have invented certain new and useful Improvements in Calculating-Machines, of which the following is a specification, reference being had to the accompanying drawings.

10 This invention relates to calculating machines, and it has for one of its objects the provision of a new and improved form and arrangement of parts for effecting operations in multiplication and addition.

15 It is another object of my invention to improve devices of this type in sundry details hereinafter pointed out.

The preferred means by which I have accomplished my objects are illustrated in the 20 accompanying drawings and are hereinafter specifically described.

In the drawings, Figure 1 is a side view of my improved machine, the outer wall of 25 which is partly broken away to show a part of the clearing or resetting mechanism; Fig. 2 is a top or plan view of my improved machine; Fig. 3 is a side view of my machine with the casing and a portion of the mechanism removed for better showing the construction and arrangement of the remaining parts; Fig. 4 is a horizontal cross-section taken substantially on line 4—4 of Fig. 3; Fig. 5 is an end view of my improved machine with the casing cut away at the end 30 to better show the construction and arrangement; Fig. 6 is an enlarged detail showing the construction and arrangement of one of the key barrels, together with the mechanism with which it is brought into operative engagement; Fig. 7 is an enlarged detail showing a central vertical section through the barrel of Fig. 6; Fig. 8 is an enlarged detail, being substantially a section on line 8—8 of Fig. 6; Fig. 9 is a fragmentary view 40 showing the connections between one of the keys and the number-devices adapted to be moved thereby; Fig. 10 is an enlarged detail showing the construction of one of the clutches by which the number-devices are 45 driven; Fig. 11 is a diagrammatic top view of one complete longitudinally-extending row of key-barrels; Figs. 12 to 20, inclusive, are diagrammatic views of barrels 1 to 9,

respectively, of Fig. 11, each figure showing the surface of the cylindrical barrel developed in two sections; Fig. 21 is a side view of a modified form of key and coöperating parts; Fig. 22 is a horizontal cross-section taken substantially on line 22—22 of Fig. 21; and Fig. 23 is a side view of still another modified form of key.

Referring to Figs. 1 to 20, inclusive, in which corresponding parts are indicated by the same reference characters,—20 indicates a base, rising from which is a frame 21. 65 The greater portion of the frame 21 and the parts supported thereby are inclosed by a casing 22 of any suitable type.

Mounted in the framework 21 are a plurality of keys 23, in the present instance 70 forty-five of such keys being shown arranged in five longitudinally-extending rows of nine each. Each of the keys 23 in the construction shown comprises a push-rod 24 having mounted thereon a finger-piece 25, a 75 cylindrical barrel 26 in which said push-rod 24 is revolvably mounted, pins 27 fixed in said barrel, and a rock-shaft 28 fixedly connected in any suitable manner with the lower end of the barrel 26. In the construction shown the push-rods 24 are square in cross-section and are adapted to slide freely through bosses 29 carried by the casing but are held against rotation relative thereto. The push-rods 24 are revolvably connected 85 with the barrels 26 by means of plates 30 secured by screws or in any other suitable manner to the barrels 26, which plates fit in circumferential grooves about the push-rods 24. The lower portions of the rock-shafts 90 28 are square in cross-section and have slidably mounted upon their lower ends pinions 31, said pinions, in the construction shown having teeth about a portion only of their peripheries. The pinions 31 are held in their 95 proper position and the keys 23 are held yieldingly in their raised position by means of springs 32 interposed upon said rock-shafts between the pinions 31 and blocks 33 mounted upon said rock-shafts. As will be 100 readily understood from the above description, the keys 23 are adapted to be pushed downward by the application of power upon the finger-pieces 25 against the action of the springs 32, the rock-shafts 28 being adapted 105 to slide freely through the pinions 31. Upon

the application of power to the pinions 31 for turning said pinions, the rock-shafts 28 are rotated, carrying with them the barrels 26, which turn relative to the push-rods 24, 5 as above explained.

- Coming now to the means for rotating the barrels 26 through the medium of the pinions 31, 34 indicates a plurality of toothed cross-bars slidably mounted upon the base 10 20, each in position to mesh with a plurality of the segmental pinions 31. The cross-bars 34 are connected at their ends by a longitudinally-extending bar 35 whereby all of said bars 34 may be moved in unison longitudinally of themselves. A lever 36 is pivotally mounted by means of a pin 37 upon the base 20, having mounted thereon a pinion 38 which meshes with a toothed portion of the adjacent cross-bar 34. There are also 15 20 provided short auxiliary levers 39—40 mounted upon the base 20 by means of pins 41—42, respectively, said levers having mounted thereon pinions 43—44 which mesh with toothed portions of the cross-bars 34. 25 The levers 36, 39 and 40 are connected so as to swing in unison by means of a longitudinally-extending bar 45. As will be readily understood, upon a stroke of the lever 36 about the pivot point 37, the pinions 38, 43 30 and 44 will be rotated in unison, causing the slidably-mounted cross-bars 34 to move laterally in unison, causing a corresponding rotation of the pinions 31 and of the barrels 26 actuated thereby. In order to assist in 35 causing the pinions 38, 43 and 44 to rotate in unison and to serve as far as possible to take up lost motion, a longitudinally-extending bar 46 is provided having toothed engagement with said three pinions. 40 Adjacent to each of the barrels 26 of the keys 23 are two slidably-mounted vertically-positioned bars 47—48 provided with engaging-blocks 49, fixed thereon, adapted to be engaged by the pins 27 of said barrels when 45 the keys are depressed in the operation of the machine. Each of the bars 47—48 is mounted to slide upon the face of a frame-plate 50, a plurality of such plates 50 being provided. As is clearly shown in Figs. 6 50 and 8, the pins 27 are spaced about the periphery of the barrels 26 at varying heights therealong, the arrangement of such pins upon the barrels being hereinafter described. As the barrels 26 are rotated through the 55 medium of the lever 36, the series of pins 27 are brought successively into position to contact the engaging blocks 49 of the bars 47—48. The barrels 26 thus constitute controllers or intermediate devices by which 60 motion is transmitted to the bars 47—48 when the keys 23 are operated. In order to indicate the proper position of the lever 36 for bringing any one of the pins 27 into precise alignment with the engaging-blocks 49, a graduated sector-plate 51 is provided,

extending laterally from the casing of the machine adjacent to said lever. The plate 51 is provided with two sets of graduating marks for indicating the proper position of the lever when swung in opposite directions, 70 as indicated by the arrows in Fig. 4, the double graduation being provided for the purpose of correcting for lost motion.

Coming now to the number-indicating mechanism,—52 indicates brackets, extending from the front portion of the frame 21, having mounted thereon the number-indicating devices. Inasmuch as these devices are of the construction and arrangement as shown and described in United States patent 75 to Horton, No. 1,016,501, it is believed that it will be unnecessary to describe such mechanism very much in detail. The mechanism comprises six number-devices, as indicated in Fig. 2, such devices being indicated by the numerals 53 to 58, respectively, each of such number-devices being in the form of a wheel, as illustrated in Fig. 9, with the numbers arranged about the periphery of the wheel, said wheels being 80 mounted upon a shaft 59 supported by the brackets 52. Each of said number-wheels is adapted to be rotated through the medium of a gear 60. Each of the gears 60, with the exception of that carried by the number-device 53, is adapted to be driven in clockwise direction in Fig. 9 through the medium of a pinion 61, a clutch 62, a pinion 63, and a toothed bar 64 which is moved longitudinally of itself by the longitudinally-extending bar 65 through the medium of an intermeshing pinion 66. The clutch 62 is arranged so that it is effective to turn the gears 60 upon the forward movement of the 85 longitudinally-extending bar 65. Each of the gears 60, with the exception of that of the number-device 58, is also adapted to be driven in clockwise direction in Fig. 9 through the medium of a gear 67, a pinion 68, a clutch 69, a pinion 70, and a vertically-positioned toothed-bar 71 which is moved longitudinally of itself by a longitudinally-extending toothed-bar 72 through the medium of a pinion 73 which intermeshes between the bar 71 and the turned end 74 of the bar 72. The clutch 69 is of the type shown in Fig. 10, so arranged that the gear 60 is turned in clockwise direction in Fig. 9 upon the rearward movement of the longitudinally-extending bar 72. Thus, when the 90 keys are operated, the registering mechanism is, in proper cases, actuated both on the direct stroke of the keys and on their return stroke. This occurs in all cases except when the controller 26 of any key is 95 turned to such position that it actuates only one of the two bars 47—48. The number-wheels 53 to 58 are also provided with suitable carrying devices, whereby upon the rotation of any one of said number-devices 100

into or past a zero-indicating position the adjacent number-wheel is given a one-step partial rotation, as is readily understood in connection with number mechanism.

5 The clearing or resetting mechanism by which all of the number-devices are adapted to be brought to a zero-indicating position is of the character shown and described in the said Horton patent. This mechanism 10 comprises a lever 75 corresponding to the lever W of the said Horton patent construction, by a complete forward and backward stroke of which lever the number-devices are all brought to their zero-indicating position. 15 Inasmuch as this clearing mechanism forms of itself no part of my present invention, it is believed that it is not necessary to further describe it herein.

Coming now to the means for actuating 20 the longitudinally-extending bars 65—72, 76 indicates a pinion intermeshing between the bar 65 and one of the bars 47, and 77 indicates a pinion intermeshing between the bar 72 and one of the bars 48. By the use of the 25 pinions 76—77, upon the downward movement of the bars 47—48 actuated by the key 23 located therebetween, the bars 65 and 72 are both moved forward or to the left in Fig. 9. Each of the bars 65—72 has pivotally 30 mounted upon its rear end a link 78, such links, in turn, being mounted upon the upper ends of bell-crank levers 79, the forward ends of which are yieldingly held in raised position by springs 80.

35 As is seen from the above description, each of the keys 23 is operatively connected with two of the number-devices 53 to 58 whereby an operative stroke of said key is adapted to rotate said two number-devices, one of said 40 number-devices being rotated upon the downward stroke of the key and the other number-device being rotated upon the upward stroke of said key as said key is moved upward by its spring 32 assisted by the 45 spring 80. It will also be seen that each of the number-devices is operatively connected with the keys of two different rows. In Fig. 9 it will be seen that the number-device 57 is connected with the key 23 shown in 50 said figure through the medium of the vertical bar 64 and the longitudinally-extending bar 65. Said number-device 57 is also connected with the adjacent key 23 (not shown) through the medium of the vertical 55 bar 71 (shown partly broken away in said Fig. 9) together with the longitudinally-extending bar 72 (also not shown in said Fig. 9) which is connected with said vertically-extending bar 71, as above described.

60 Referring now particularly to Figs. 11 to 20 for a description of the several keys and the manner in which they operate, the showing of Fig. 11 represents diagrammatically any one of the longitudinally-extending 65 rows of keys. The black-faced numerals 1

to 9 in these figures represent the numerals found upon the finger-pieces of the several keys as shown in Fig. 2. The barrel or controller 26 of each of the keys is shown as provided with a plurality of actuating pins, 70 such as are indicated in the other figures by the numeral 27. The light-faced numerals leading to the several pins are used to indicate the height at which the various pins are located on the barrel of the key. The pins 75 upon the right-hand side of the keys in this figure are those which are adapted to be brought into engagement with the engaging-blocks of the bars 47, while the pins upon the left-hand side are those adapted to be 80 brought into engagement with the engaging-blocks of the bars 48. The light-faced numerals indicate that the pins are arranged at such a height upon the barrels as to cause 85 upon the depression of the barrel a movement of the bar 47 or 48 a corresponding number of units-distance,—that is to say, such a distance as to cause the rotation of the number-wheel actuated thereby a corresponding number of steps. Each of the 90 keys is shown in Fig. 11 in the position which such key holds when the lever 36 stands at its "1" position. When the lever 36 is moved to its "2" position, each of the controllers is rotated to bring a different 95 pin into operative position to engage the blocks 49 of the bars 47—48. Thus with the lever 36 at its "1" position, upon the actuation of the several keys 1 to 9 the bars 47 are given a movement of one to nine units 100 value, respectively, as shown by the light-faced numerals leading to the pins which are the nearest adjacent in said figure to Figs. 12 to 16, while the bar 48 is given no movement, as indicated by the absence of any pins 105 diametrically opposite the pins 1 to 9 referred to. With the lever 36 moved to its "2" position, thus turning the barrels or controllers in Fig. 11 slightly in clockwise direction, upon the actuation of the several keys 110 1 to 9 the bars 47 are given a movement of two units value, four units, six, eight, none, two, four, six, and eight units, respectively, as shown by the light-faced numerals leading 115 to the pins next to the right in Fig. 11 of the pins 1 to 9 above referred to. With said lever 36 at its said "2" position, upon the actuation of the keys 1 to 4, the bar 48 is not moved, and upon each actuation of the 120 keys 5 to 9 the bar 48 is given a movement of one unit value, as shown by the light-faced numerals leading to the pins which are then turned into position to coöperate with the bar 48. Likewise, with the lever 36 at its "3" position, upon the actuation of the 125 keys 1 to 9 the bars 47 are given a movement of three units value, six units, nine, two, five, eight, one, four, and seven units, respectively. With said lever 36 at its said "3" 130 position, upon the actuation of the keys 1

to 3 the bar 48 is not moved, upon each actuation of the keys 4 to 6 the bar is given a movement of one unit, and upon the actuation of each of the keys 7 to 9 the bar 48 is given a movement of two units value.

If it were desired to find the product of 3 and 7, with the lever 36 in its "3" position the "7" key of the first or units row of keys would be depressed,—that is to say, the row 10 of keys nearest to the clearing handle 75 in Fig. 2. Upon such actuation of the "7" key the bar 47 would be moved one unit distance and the bar 48 would be moved two units distance, thus turning the number-15 wheel 58 one step in advance on the downward or direct stroke of the key, and the wheel 57 two steps in advance on the upward or return stroke of the key, giving a reading of 21. As will be readily understood and 20 as will be seen from an inspection of Figs. 11 to 20, if the lever 36 were placed at its "7" position and the "3" key were depressed, an exactly similar result would follow. If it were desired to multiply 30 and 7, or 3 and 25 70, with the lever 36 at its "3" position, the "7" key of the second or tens row would be depressed, moving downward the second set 30 of bars 47 and 48 a distance of one and two steps, respectively, causing a rotation of the number-wheels 57 and 56 one and two steps on the direct and return strokes of the key, respectively, obtaining a reading of 210.

In the description hereinabove, all references to the readings and indications of the 35 number-devices have been meant to apply in case the number-devices were "cleared" or reset before each actuation of a key. If such clearing were not performed, the machine would multiply in the manner above 40 set forth but the results would be added in as a portion of the total reading rather than being indicated separately.

As will be readily understood, two or more keys of different rows can be operated at the 45 same time. That is to say, in multiplying 3 and 25 the lever 36 would be set at its "3" position. The correct reading upon the number-devices can then be obtained either by depressing the "5" key of the first row 50 and subsequently depressing the "2" key of the second row, or by depressing said two keys simultaneously.

Referring now to Figs. 21 and 22, which show a modified form of structure, the corresponding parts are indicated by the same reference characters, but with the addition of an exponent "a." In these figures the barrel 26 and the engaging-blocks 49 are omitted, an alternative construction being 60 used instead. The key is provided with a cross-bar 81 which is adapted, as it is rotated with the key, to engage the different faces of differential engaging-blocks 82—83, respectively, mounted upon the bars 47^a—48^a, 65 respectively.

In Fig. 23 is illustrated still another form of device, the parts which correspond to the first-described construction being indicated by the same reference characters, but with the additional of an exponent "b." 70 In this construction the barrel 26 with its projecting pins 27 is omitted, its place being taken by a barrel 84 which is notched differentially to provide engaging-faces for the engaging-blocks 49^b, such engaging-faces being located in simulation to the position of the pins in the construction first described. 75

While I have shown the keys 23 movable and the bars 47—48 adapted to be moved only through the actuation of the key, it will 80 be understood that I do not wish to limit myself to this particular construction, except as hereinafter claimed, the essential point being that the keys and the parts actuated thereby shall be movable relative to 85 each other, one or the other of said parts being arranged differentially so that as the relative position of said parts is changed a differential actuation of the key-actuated parts shall occur as described. While I 90 have shown the keys or controllers 26 with the differentially-arranged pins 27 as being rotatable into their different operative positions and prefer to so embody my invention, it will be understood that I do not limit myself in this way, except as hereinafter specifically claimed, it being sufficient, so far as a differential controller movable into different operative positions is concerned, that suitable adjusting means be provided by the 100 operation of which the keys or controllers are shifted as desired to their different operative positions. 95

That which I claim as my invention, and desire to secure by Letters Patent, is,— 105

1. In a calculating machine, the combination with registering devices and actuating mechanism therefor, of a key for operating said actuating mechanism, said key comprising a differential member adapted to be 110 adjusted to vary according to a predetermined series the extent to which said registering devices are actuated by each operation of said key.

2. In a calculating machine, the combination with registering devices and actuating mechanism therefor, of a key for operating said actuating mechanism, said key comprising a differential member adapted to be 120 adjusted to vary according to a predetermined series the extent to which said registering devices are actuated by each operation of said key, and means for so adjusting said differential member. 115

3. In a calculating machine, the combination with registering devices and actuating mechanism therefor, of a key for operating said actuating mechanism, said key comprising a differential member adapted to be 125 rocked to vary according to a predetermined 120

series the extent to which said registering devices are actuated by each operation of said key.

4. In a calculating machine, the combination with registering devices and actuating mechanism therefor, of a key for operating said actuating mechanism, said key comprising a differential member adapted to be rocked to vary according to a predetermined series the extent to which said registering devices are actuated by each operation of said key, and means for rocking said differential member.

5. In a calculating machine, the combination with registering devices and actuating mechanism therefor, of a key for operating said actuating mechanism, said key comprising a differential member mounted thereupon and movable to vary according to a predetermined series the extent to which said registering devices are actuated by the operation of said key.

6. In a calculating machine, the combination of a key, number-devices adapted to operate to indicate a number, means adapted to be actuated by the operation of said key for moving said number-devices, and means for rotating said key for bringing different portions of the key into operative position relative to said key-actuated means whereby the key acts differentially in moving said number-devices for indicating successive numbers of an arithmetical progression.

7. In a calculating machine, the combination of a key comprising a cylinder having graduated bearing parts, number-devices adapted to coöperate to indicate a number, means adapted to be actuated by the operation of said key through the medium of said graduated bearing parts for moving said number-devices, and means for rotating said key for bringing different bearing parts of the key into operative position relative to said key-actuated means whereby the key acts differentially in moving said number-devices for indicating successive numbers of an arithmetical progression.

8. In a calculating machine, the combination of a key comprising a cylinder provided with a plurality of pins, number-devices adapted to coöperate to indicate a number, means adapted to be actuated by the operation of said key through the medium of said pins for moving said number-devices, and means for rotating said key for bringing different pins of the key into operative position relative to said key-actuated means whereby the key acts differentially in moving said number-devices for indicating successive numbers of an arithmetical progression.

9. In a calculating machine, the combination of a key comprising a cylinder provided with a plurality of pins spaced about its periphery at different heights therealong,

number-devices adapted to coöperate to indicate a number, means adapted to be actuated by the operation of said key through the medium of said pins for moving said number-devices, and means for rotating said key for bringing different pins of the key into operative position relative to said key-actuated means whereby the key acts differentially for moving said number-devices for indicating successive numbers of an arithmetical progression.

10. In a calculating machine, the combination of a key comprising a cylinder provided with a plurality of pins spaced about its periphery at different heights therealong, number-devices adapted to coöperate to indicate a number, means adapted to be actuated by the operation of said key through the medium of said pins for moving said number-devices, and means for rotating said key for bringing different pins of the key into operative position relative to said key-actuated means whereby the key acts differentially for moving said number-devices, the arrangement of said pins upon said cylinder being such that upon the operation of said key in successive operative positions as the key is rotated in one direction said number-devices indicate the numbers of an increasing arithmetical progression.

11. A calculating machine, comprising registering devices, actuating mechanism therefor, and a plurality of keys for operating said actuating mechanism, each of said keys comprising a differential member adjustable to vary according to a predetermined series the extent to which said registering devices are actuated by each operation of its key.

12. A calculating machine, comprising registering devices, actuating mechanism therefor, a plurality of keys for operating said actuating mechanism, each of said keys comprising a differential member adjustable to vary according to a predetermined series the extent to which said registering devices are actuated by each operation of its key, and means for so adjusting said differential members.

13. A calculating machine, comprising registering devices, actuating mechanism therefor, a plurality of keys for operating said actuating mechanism, each of said keys comprising a differential member adjustable to vary according to a predetermined series the extent to which said registering devices are actuated by each operation of its key, and means for simultaneously and similarly adjusting all of said differential members.

14. In a calculating machine, the combination of a key, two number-devices adapted to coöperate to indicate a number, means adapted to be actuated by the operation of said key for moving one of said number-devices, carrying means whereby the opera-

5 tive movement of said last-named number-device through successive complete phases causes a corresponding movement of said other number-device, and other means likewise adapted to be actuated by the operation 70
5 of said key for moving the last-named number-device.

15. In a calculating machine, the combination of a key, two number-devices adapted 10 to coöperate to indicate a number, means adapted to be actuated by the operative movement of said key in one direction for moving one of said number-devices, and other means adapted to be actuated by the 15 operative movement of said key in the opposite direction for moving the other of said number-devices.

16. In a calculating machine, the combination of a key, two number-devices adapted 20 to coöperate to indicate a number, two bars adapted to be actuated by an operative movement of said key, connections between one of said bars and one of said number-devices whereby an operative movement of 25 said bar serves to give said number-devices an operative movement, and connections between the other of said bars and the other of said number-devices whereby an operative movement of said last-named bar 30 serves to give the number-device with which it is connected an operative movement.

17. In a calculating machine, the combination of a key, two number-devices adapted 5 to coöperate to indicate a number, two bars adapted to be actuated by an operative movement of said key, connections between one of said bars and one of said number-devices whereby an operative movement of 10 said bar in one direction serves to give said number-device an operative movement, and connections between the other of said bars and the other of said number-devices whereby an operative movement of said last-named bar in the opposite direction serves 15 to give the number-device with which it is connected an operative movement.

18. In a calculating machine, the combination of a key, two number-devices adapted 50 to coöperate to indicate a number, two bars adapted to be actuated by an operative movement of said key, yielding means against the action of which said bars are moved by said key, connections between one of said bars and one of said number-devices 55 whereby an operative movement of said bar against the action of its yielding means serves to give said number-device an operative movement, and connections between the other of said bars and the other of said 60 number-devices whereby the return movement of said last-named bar under the influence of its yielding means serves to give the number-device with which it is connected an operative movement.

65 19. In a calculating machine, the combi-

nation of a key, a number-device, means adapted upon an operative stroke of said key in one direction to give said number-device an operative movement, a second key, and means adapted upon an operative stroke 70 of said second key in the opposite direction to give said number-device an operative movement.

20. In a calculating machine, the combination of two keys, a number-device, yielding means tending to hold said keys against movement out of normal position, means adapted upon an operative stroke of one of said keys against the action of said yielding means to give said number-device an operative movement, and means adapted upon the movement of the other of said keys into normal position under the influence of said yielding means to give said number-device 80 an operative movement.

85 21. In a calculating machine, the combination of a series of keys, yielding means tending to hold said keys in normal position, a series of number-devices adapted to indicate respectively the units, tens, etc., of 90 a number, means for each of said keys adapted to be actuated by an operative stroke of said key against the action of said yielding means for giving an operative movement to that number-device which corresponds in the series of number-devices to said key in the series of keys, and means for each of the keys in said series adapted to be actuated by an operative stroke of said key into normal position under the influence of 100 said yielding means for giving an operative movement to that number-device which is one step in advance in the series of number-devices.

95 22. In a calculating machine, the combination of a key, number-devices adapted to coöperate to indicate a number, bars at opposite sides of said key adapted to be actuated by said key for moving said number-devices, and means for rotating said key 110 for bringing different parts thereof into operative position relative to said bars.

115 23. In a calculating machine, the combination of a key comprising two sets of pins arranged thereabout, number-devices adapted to coöperate to indicate a number, bars at opposite sides of said key each of which bars is adapted to be engaged by one of the pins of one of said sets and to be actuated thereby for moving said number-devices, and 120 means for rotating said key for bringing different pins into operative position relative to said bars.

125 24. In a calculating machine, the combination of a key comprising two sets of pins each set arranged circumferentially upon one-half the periphery of the key, number-devices adapted to coöperate to indicate a number, bars at opposite sides of said key each of which bars is adapted to be engaged 130

by one of the pins of one of said sets and to be actuated thereby for moving said number-devices, and means for rotating said key for bringing different pins into operative position relative to said bars.

25. In a calculating machine, the combination of a key comprising two sets of pins each set arranged circumferentially upon one-half of the periphery of the key, number-devices adapted to coöperate to indicate a number, means adapted to be actuated by said key through the medium of said pins for moving said number-devices, and means for rotating said key to successive positions for bringing different pins into operative position for moving said number-devices for indicating successively the numbers of an increasing arithmetical progression, one set of pins being arranged to effect the proper successive movements of the key-actuated means for indicating successively the units and the other set of pins being arranged to effect the proper successive movements for indicating successively the tens.

26. In a calculating machine, the combination of a vertically-movable key comprising two sets of pins each set arranged circumferentially upon one-half of the periphery of the key, number-devices adapted to coöperate to indicate a number, means adapted to be actuated by said key through the medium of said pins for moving said number-devices, and means for rotating said key to successive positions for bringing different pins into operative position for moving said number-devices for indicating successively the numbers of an increasing arithmetical progression, one set of pins being arranged at the proper heights for effecting the proper successive indications of units and the other set of pins being arranged at the proper heights for effecting the proper successive indications of tens.

27. In a calculating machine, the combination of a vertically-movable key comprising two sets of pins each set arranged circumferentially upon one-half of the periphery of the key, number-devices adapted to coöperate to indicate a number, means adapted to be actuated by said key through the medium of said pins for moving said number-devices, and means for rotating said key to successive positions for bringing different pins into operative position for moving said number-devices for indicating successively the numbers of an increasing arithmetical progression, one set of pins being arranged to effect proper successive indications in one column and the other set of pins being arranged to effect proper successive indications in the next-higher column.

28. In a calculating machine, the combination of a plurality of keys, a plurality of bars one for each key adapted to be actuated

by said keys, a plurality of pinions one for each bar having toothed engagement with said bars, a longitudinally-extending toothed bar engaging said pinions, and number-indicating means actuated by the movement of said last-named bar.

29. In a calculating machine, the combination of a plurality of keys, a plurality of bars one for each key adapted to be actuated by said keys, a plurality of pinions one for each bar having toothed engagement with said bars, a longitudinally-extending toothed bar engaging said pinions, a plurality of additional bars one for each key adapted to be actuated by said keys, a plurality of additional pinions one for each of said last-named bars having toothed engagement with said bars, an additional longitudinally-extending toothed bar engaging said last-named pinions, and number-indicating means actuated by the movement of said two longitudinally-extending bars.

30. In a calculating machine, the combination of a plurality of pairs of longitudinally-extending toothed bars, number-indicating means actuated by the movement of said bars, and actuating means for each pair of said bars, comprising a plurality of pinions engaging the teeth of said bars, one pinion being provided for each bar, a plurality of toothed bars arranged at an angle to said longitudinally-extending bars, one for each of said pinions, and a plurality of keys adapted for actuating said second-named bars.

31. In a calculating machine, the combination of a plurality of slidably-mounted keys, yielding means tending to hold said keys in normal position longitudinally of themselves, and means for rotating all of said keys in unison.

32. In a calculating machine, the combination of a plurality of slidably-mounted keys, yielding means tending to hold said keys in normal position longitudinally of themselves, pinions rotatable with said keys, toothed cross-bars each engaging a plurality of said pinions, a longitudinally-extending bar connecting said cross-bars, and a lever for moving said cross-bars in unison for rotating said keys.

33. In a calculating machine, the combination of a plurality of slidably-mounted keys, yielding means tending to hold said keys in normal position longitudinally of themselves, pinions rotatable with said keys, toothed cross-bars each engaging a plurality of said pinions, a longitudinally-extending bar connecting said cross-bars, a lever, and a pinion mounted on said lever and engaging one of said cross-bars whereby a stroke of said lever serves to move said cross-bars for rotating said keys.

34. In a calculating machine, the combination of a plurality of slidably-mounted

- keys, yielding means tending to hold said keys in normal position longitudinally of themselves, pinions rotatable with said keys, toothed cross-bars each engaging a plurality of said pinions, a longitudinally-extending bar connecting said cross-bars, a plurality of levers, means for causing said levers to swing in unison, and pinions mounted on said levers and engaging a plurality of said cross-bars whereby a stroke of said levers serves to move said cross-bars for rotating said keys.
35. In a calculating machine, the combination of a plurality of slidably-mounted keys, yielding means tending to hold said keys in normal position longitudinally of themselves, pinions rotatable with said keys, toothed cross-bars each engaging a plurality of said pinions, a longitudinally-extending bar connecting said cross-bars, a plurality of levers, a longitudinally-extending bar connecting said levers and causing them to swing in unison, pinions mounted on said levers and engaging a plurality of said cross-bars whereby a stroke of said levers serves to move said cross-bars for rotating said keys, and a third longitudinally-extending bar having toothed engagement with said last-mentioned pinions for assisting in causing them to rotate together whereby the lost motion may be minimized.
36. In a calculating machine, the combination of a plurality of slidably-mounted keys, yielding means tending to hold said keys in normal position longitudinally of themselves, a lever adapted by a stroke thereof to rotate said keys, and a scale for indicating desired positions of said lever to secure the required degrees of rotation of said keys.
37. In a calculating machine, the combination of a plurality of slidably-mounted keys, yielding means tending to hold said keys in normal position longitudinally of themselves, a lever adapted by a stroke thereof to rotate said keys, and a double scale for indicating desired positions of said lever as it is swung in either direction to secure the required degrees of rotation of said keys, the double scale serving to correct for lost motion.
38. A calculating machine, comprising registering devices, actuating mechanism therefor, a plurality of series of keys for operating said actuating mechanism, the keys of each series representing numbers from 1 to 9, inclusive, and the several series representing a decimal progression, and intermediate adjustable differential mechanism for varying the extent to which said registering devices are actuated by the operation of said keys.
39. A calculating machine, comprising registering devices, actuating mechanism therefor, a plurality of series of keys for operating said actuating mechanism, the keys of each series representing numbers from 1 to 9, inclusive, and the several series representing a decimal progression, and intermediate adjustable differential devices for varying the extent to which said registering devices are actuated by the operation of said keys, and means for simultaneously and similarly adjusting all of said differential devices.
40. A calculating machine, comprising registering devices, actuating mechanism therefor, a plurality of series of keys for operating said actuating mechanism, the keys of each series representing numbers from 1 to 9, inclusive, and the several series representing a decimal progression, and intermediate rotary differential mechanism for varying the extent to which said registering devices are actuated by the operation of said keys.
41. In a calculating machine, the combination of registering mechanism, means comprising a rotary controller for actuating said registering mechanism, and means for rotating said controller to vary the extent to which the registering mechanism is actuated by a single operation of said actuating means.
42. In a calculating machine, the combination of registering mechanism, means comprising a plurality of controllers for actuating said registering mechanism, and means for simultaneously and similarly adjusting all of said controllers to vary the extent to which the registering mechanism is actuated by a single operation of one of said controllers.
43. In a calculating machine, the combination of registering mechanism, a controller, a pair of actuating members positioned on opposite sides of said controller and adapted to coöperate therewith for actuating said registering mechanism, and means for adjusting said controller to vary the extent to which the registering mechanism is actuated by a single operation of said controller.
44. In a calculating machine, the combination of registering mechanism, a controller, a pair of actuating members positioned on opposite sides of said controller and adapted to coöperate therewith for actuating said registering mechanism, and means for adjusting said controller successively to a plurality of operative positions whereby upon successive operations of said controller in successively-different operative positions said registering mechanism is caused to register successively the numbers of an arithmetical progression.
45. In a calculating machine, the combination with a frame, registering devices and actuating mechanism therefor, of a plurality of keys for operating said actuating

- mechanism, said keys being mounted in fixed situations in said frame, and differential mechanism adapted to be adjusted to vary according to a predetermined series the extent to which said registering devices are actuated by each operation of the keys. 5
46. In a calculating machine, the combination with a frame, registering devices and actuating mechanism therefor, of a plurality of keys for operating said actuating mechanism, said keys being mounted in fixed situations in said frame, differential mechanism adapted to be adjusted to vary according to a predetermined series the extent to which said registering devices are actuated by each operation of the keys, and means for simultaneously and similarly adjusting the differential mechanism in reference to each of the keys. 10
47. In a calculating machine, the combination of registering mechanism, a plurality of keys adapted to be operated separately to actuate the registering mechanism, each of said keys comprising an intermediate device adapted to be adjusted to vary the extent to which the registering mechanism is actuated by the operation of such key, and means for adjusting the intermediate devices of all the keys in unison. 15
48. In a calculating machine, the combination of registering mechanism, a plurality of keys adapted to be operated separately to actuate the registering mechanism, each of said keys comprising an intermediate device adapted to be adjusted to vary the extent to which the registering mechanism is actuated by the operation of such key, and means for simultaneously and equally adjusting the intermediate devices of all the 20 keys. 30
49. In a calculating machine, the combination of registering mechanism, a plurality of keys adapted to be operated separately to actuate the registering mechanism, each of said keys comprising an intermediate device adapted to be adjusted to vary the extent to which the registering mechanism is actuated by the operation of such key, and means independent of the operation of the keys for 25 adjusting the intermediate devices of the several keys. 45
50. In a calculating machine, the combination of registering mechanism, a plurality of keys adapted to be operated separately to actuate the registering mechanism, each of said keys comprising a rotary intermediate device adapted to be adjusted to vary the extent to which the registering mechanism is actuated by the operation of such key. 55
51. In a calculating machine, the combination of registering mechanism, a plurality of keys adapted to be operated separately to actuate the registering mechanism, each of said keys comprising a rotary intermediate device adapted to be adjusted to vary the extent to which the registering mechanism is actuated by each operation of the keys. 60
- extent to which the registering mechanism is actuated by the operation of such key, and means for rotating the several intermediate devices in unison. 65
52. In a calculating machine, the combination of registering mechanism, a plurality of keys, a differential device associated with each of said keys and adapted to be actuated by the operation thereof, and a pair of actuating members coöperating with said differential device to actuate said registering mechanism. 70
53. In a calculating machine, the combination of registering mechanism, a plurality of keys, a differential device associated with each of said keys and adapted to be actuated by the operation thereof, a pair of actuating members coöperating with said differential device to actuate said registering mechanism, and means for adjusting said differential devices to vary the extent to which the registering mechanism is actuated by the operation of the keys. 75
54. A calculating machine, comprising registering mechanism, a key movable alternately in opposite directions, and a plurality of devices operated by said key for actuating consecutive parts of said registering mechanism. 80
55. A calculating machine, comprising registering mechanism, a key movable alternately in opposite directions, and a plurality of devices operated by said key for actuating consecutive parts of said registering mechanism on the direct and on the return strokes of said key respectively. 85
56. A calculating machine, comprising registering devices, a key movable alternately in opposite directions, and means actuated by the operation of the key to actuate said registering devices on the direct stroke of the key and also on the return stroke thereof. 90
57. A calculating machine, comprising registering devices, a key movable alternately in opposite directions, and a plurality of devices actuated by the operation of said key to actuate consecutive parts of said registering devices respectively on the direct and on the reverse strokes of said key. 95
58. A calculating machine, comprising registering devices, a key, a differential controller, and means actuated by said controller for advancing consecutive parts of said registering devices complementally. 105
59. A calculating machine, comprising registering devices, a key, a differential controller, means actuated by said controller for advancing consecutive parts of said registering devices complementally, and means for varying the extent to which said controller operates said registering devices according to a predetermined series. 110
60. A calculating machine, comprising registering devices, a plurality of keys, a 115

plurality of differential controllers associated with said keys, and a plurality of actuating devices associated with each of said controllers and actuated thereby to advance consecutive portions of said registering devices complementally.

61. A calculating machine, comprising registering devices, a plurality of keys, a plurality of differential controllers associated with said keys, a plurality of actuating devices associated with each of said controllers and actuated thereby to advance consecutive portions of said registering devices complementally, and means for varying the operation of the several controllers according to a predetermined series.
62. A calculating machine, comprising

registering devices, a plurality of keys, a plurality of differential controllers associated with said keys, and a plurality of actuating devices associated with each of said controllers and actuated thereby to advance consecutive portions of said registering devices complementally, one of the actuating devices associated with each controller being arranged to actuate the registering devices upon the direct stroke and the other on the return stroke thereof.

JESSE SPURGEON.
